UNITED STATES PATENT OFFICE.

GEORGE FREDERICK VOIT, OF NEW YORK, N. Y., ASSIGNOR TO SIGMUND FEUST AND DAVID WOLF, OF SAME PLACE.

DESIGN FOR A DRAWER-PULL AND BACK PLATE.

SPECIFICATION forming part of Design No. 20,203, dated October 14, 1890.

Application filed August 25, 1890. Serial No. 363,051. Term of patent 3½ years.

To all whom it may concern:

Be it known that I, GEORGE FREDERICK VOIT, a citizen of the United States, residing at New York, in the county of New York and State of New York, have invented and produced a new and original Design for Drawer-Pulls and Back Plates, of which the following is a specification, reference being had to the accompanying drawings, forming part thereof.

10 Figure 1 is a front view of a drawer-pull and back plate showing my design. Fig. 2 is a top view of the same, these two views being deemed necessary to fully illustrate my design.

15 The center piece A of the back plate is connected with the two end pieces B by a scroll C, carrying studs D, to which the handle E is affixed. The center piece A is a raised piece in the shape of an X, ornamented on the top 20 with three scallops a, and round holes a', in the middle with oval intersections a'', and

also ornamented at the bottom with a trefoil a''. To both sides of this X-shaped center piece, connected by small disks, is a C-shaped scroll C, the inner wider part of which carries 25 the studs D and handle. The outer part of this scroll runs out into a square-shaped piece B, an ornamented inside with a small half-circle b', and outside, extending to the outer edge, a flat piece b'', with a round disk b''' at the end. 30 The handle E consists of a so-called "manuscript" scroll c, attached to curved ends or connection-pieces c'.

Having thus described my invention, what I claim is—

35 The design for a drawer-pull and back plate, as herein shown and described.

GEORGE FREDERICK VOIT.
